United States Patent Office

Des. 233,814
Patented Dec. 3, 1974

233,814

GRATED CHEESE BOWL

Augusto Salviate, Corso Mario Abbiate, 110,
Vercelli, Italy

Filed June 11, 1973, Ser. No. 369,050

Term of patent 14 years

Int. Cl. D7—01

U.S. Cl. D7—17

Fig. 1

Fig. 2

Fig. 3

FIG. 4

FIG. 5

FIG. 1 is a top plan view of a grated cheese bowl showing my new design;

FIG. 2 is a side view thereof, the side opposite being a mirror image;

FIG. 3 is a bottom plan view thereof;

FIG. 4 is a front view thereof; and

FIG. 5 is a rear view thereof.

I claim:

The ornamental design for a grated cheese bowl, as shown and described.
